UNITED STATES PATENT OFFICE.

CHESTER T. ALLCUTT, OF WILKINSBURG, PENNSYLVANIA, ASSIGNOR TO WESTINGHOUSE ELECTRIC & MANUFACTURING COMPANY, A CORPORATION OF PENNSYLVANIA.

PROTECTIVE DEVICE.

1,371,538.

Specification of Letters Patent. Patented Mar. 15, 1921.

Application filed January 29, 1917. Serial No. 145,326.

To all whom it may concern:

Be it known that I, CHESTER T. ALLCUTT, a citizen of the United States, and a resident of Wilkinsburg, in the county of Allegheny and State of Pennsylvania, have invented a new and useful Improvement in Protective Devices, of which the following is a specification.

My invention relates to protective devices 10 and particularly to devices for indicating when the temperature of the rotatable member of a dynamo-electric machine reaches a predetermined value.

The object of my invention is to provide 15 a device of the above indicated character that shall be actuated by the centrifugal force of the rotatable member of the machine when the temperature of the rotatable member exceeds a predetermined value only.

20 In one form of my invention, I provide a receptacle that is disposed in the body portion of the rotatable member having a substance, such as an alloy of tin, bismuth and lead therein, which is adapted to become a 25 fluid at a predetermined temperature. An alarm circuit is provided that is adapted to be closed when the substance is so displaced by the centrifugal force of the rotatable member or armature that it bridges the 30 terminals of the alarm circuit.

In the accompanying drawings, Figure 1 is a diagrammatic view of a temperature-protective device embodying my invention, and Fig. 2 is a diagrammatic view of a 35 modified form of protective device embodying my invention.

An armature or rotatable member 1 that is to be protected against excessive rises in temperature is mounted on a shaft 2 which 40 is grounded. A conducting receptacle 3 is disposed within the body portion of the armature 1 and is provided with an insulating member 4 at one end thereof through which extends a terminal member 5. A 45 fusible substance 6, such as an alloy of tin, bismuth and lead having a relatively low melting point, is disposed in the receptacle 3. The conducting casing of the receptacle 3 is electrically connected to the shaft 2, and a slip ring 7, that is insulated from the 50 shaft 2, is operatively connected to the terminal 5. A brush or other current-collecting device 8 is adapted to engage the slip ring 7 and is operatively connected through 55 a source 9 of electromotive force and an

audible or visible signal device, such as a bell 10, to the ground.

Since the substance 6 is normally retained out of engagement with the terminal 5, the circuit through the bell 10 is maintained in 60 its open position. However, when the temperature of the armature 1 increases to such value that the substance 6 becomes a fluid, the centrifugal force of the armature 1 will cause it to be displaced to such position that 65 it will bridge the space between the terminal 5 and the conducting casing of the receptacle 3. This will complete a circuit through the bell 10 for the purpose of indicating that 70 the temperature of the armature 1 has exceeded a predetermined value. When the signal device indicates that the temperature of the armature has exceeded a predetermined value, it is desirable to open the circuit and bring the armature to rest in substantially the position shown in Fig. 1 of 75 the drawings. When the armature is brought to rest in this position, the substance 6 will assume its lowermost position and, when the temperature of the armature 80 decreases to a predetermined value, it will solidify to preclude the completion of the circuit through the bell 10 until the temperature of the armature 1, when operating, again exceeds a predetermined value. 85

If it is not feasible to bring the armature 1 to rest in a predetermined position, I provide two receptacles 11 and 12, substantially as shown in Fig. 2 of the drawings, that are disposed in the body of the armature 1 at 90 opposite sides thereof with respect to each other. The casing of the receptacle 11 is connected to the shaft 2, and the casing of the receptacle 12 is connected to the slip ring 7. The terminal 5 of the receptacle 11 95 is connected to the terminal 5 of the receptacle 12 and the collector brush 8 is connected to ground through the source 9 of electromotive force and the trip coil 13 of a circuit interrupter 14. The circuit interrupter 14 may be adapted to control a circuit 100 15 that may constitute the main feeder circuit of the machine to be protected.

By the use of the device shown in Fig. 2 of the drawings, it is immaterial in which 105 position the armature 1 is brought to rest because the substance 6 must be in engagement with both of the terminals 5 before the trip coil 13 is energized. That is, the temperature of the armature 1 must exceed a 110

predetermined value and the armature 1 must be rotating at a predetermined speed in order to effect the tripping of the interrupter 14.

5 While I have shown my invention in its preferred forms, it will be understood that it is not so limited and that various modifications may be made therein without departing from the spirit and scope of the invention as set forth in the appended claims.

I claim as my invention:

1. The combination with a rotatable armature and a circuit, of a receptacle disposed within the armature and having a fusible substance therein that is adapted to be displaced by the movement of the armature only under predetermined conditions to complete the circuit.

2. A device for a dynamo-electric machine comprising a receptacle disposed within the rotatable member of the machine and having a fusible substance therein, and a circuit, said fusible substance being adapted to complete the circuit only when the temperature of the movable member reaches a predetermined value.

3. A device for a dynamo-electric machine comprising a receptacle disposed with-

in the armature of the machine and having a fusible substance therein, and a circuit, 30 said fusible substance being adapted to be so displaced by the movement of the armature as to complete the circuit only when the temperature of the armature reaches a predetermined value.

4. The combination with a dynamo-electric machine, of two receptacles disposed in the armature of the machine at opposite sides thereof, and an electric circuit, said receptacles containing a fusible substance that 40 is adapted to be displaced by the movement of the armature to effect a closure of the electric circuit when the temperature of the armature exceeds a predetermined value.

5. The combination with a dynamo-electric machine, of two receptacles disposed in the rotatable member of the machine at opposite sides thereof, and an electric circuit, said receptacles containing a fusible substance that is adapted to be so displaced under predetermined conditions that the electric circuit is rendered operative.

In testimony whereof I have hereunto subscribed my name this 19th day of January, 1917.

CHESTER T. ALLCUTT.
